UNITED STATES PATENT OFFICE

150,104

DESIGN FOR A LIGHTING FIXTURE

Albert L. Arenberg, Highland Park, and Edward C. Zimmerman, Winnetka, Ill., assignors to Patent License Corporation, Chicago, Ill., a corporation of Illinois

Application January 10, 1947, Serial No. 136,050

Term of patent 14 years

(Cl. D48—23)

To all whom it may concern:

Be it known that we, Albert L. Arenberg and Edward C. Zimmerman, citizens of the United States, residing at Highland Park, in the county of Lake and State of Illinois, and at Winnetka, in the county of Cook and State of Illinois, respectively, have invented a new, original, and ornamental Design for a Lighting Fixture, of which the following is a specification, reference being had to the accompanying drawing, forming a part thereof.

In the drawing:

Fig. 1 is a bottom perspective view of a lighting fixture showing my new design;

Fig. 2 is a view in longitudinal vertical section through the fixture, substantially on line 2—2 of Fig. 3; and

Fig. 3 is a bottom plan view of the fixture.

The characteristic features of our design are shown in full lines in the drawing.

We claim:

The ornamental design for a lighting fixture, substantially as shown and described.

ALBERT L. ARENBERG.
EDWARD C. ZIMMERMAN.
